(57) **CLAIM**

The ornamental design for a beverage container lid, as shown and described.

DESCRIPTION

FIG. 1 is a perspective view of a beverage container lid according to the invention;

FIG. 2 is a front view of the beverage container lid of FIG. 1; FIG. 3 is a plan view of the beverage container lid of FIG. 1; FIG. 4 is a right-hand side view of the beverage container lid of FIG. 1, wherein a left-hand side view (not shown) is a mirror image of the right-hand side view;

FIG. 5 is a rear view of the beverage container lid of FIG. 1; and,

FIG. 6 is an inverted plan view of the beverage container lid of FIG. 1.

The broken lines in the drawings depict environmental subject matter only and form no part of the claimed design.
